LIGHTNING ARRESTER

Edouard Gomonet, Paris, France, assignor to Société Anonyme pour les Applications de l'Électricité et des Gaz Rares-Etablissements Claude-Paz et Silva, Paris, France

Application February 10, 1947, Serial No. 727,552
In France February 25, 1946

5 Claims. (Cl. 250—27.5)

1

My invention relates to overvoltage cutouts, hereafter named "lightning arresters," which are used to protect electrical equipments against possible overvoltages.

It is known to use as lightning arrester an electric discharge apparatus with low pressure gaseous filling, so designed as to start before the overvoltage has risen to a dangerous value and then to divert to earth a portion of the electrical energy sufficient for the desired protection.

Whenever the voltage across the discharge apparatus reaches the starting voltage of this apparatus, the discharge starts in the form of a "glow discharge," the glow covering then a small part of the cathode area. If the voltage rises, the discharge current grows up and the cathode glow spreads gradually over the entire cathode area. If the magnitude of the disturbance is sufficiently high, the discharge turns into an arc discharge; the discharge concentrates then on the cathode in a cathode spot the area of which is small but the temperature high. This hard working condition is liable to modify the characteristics of the lightning arrester, specially its starting voltage.

One object of the invention is to provide a simple, easy to manufacture and reliable lightning arrester.

Another object is to provide a lightning arrester which keeps its characteristics constant, specially its starting voltage, which depends, inter alia, on the superficial condition of the electrodes.

Still another object is to provide a lightning arrester, of small overall dimensions and comprising no movable part, able to sustain strong currents without its starting voltage being altered.

According to the invention, each electrode of the lightning arrester comprises at least two zones, their relative places and differences, if any, in the superficial compositions and in their forms being such that the discharge starts in all cases on a first zone, named "starting zone," without an arc discharge occurring there and that if the discharge turns into an arc discharge, the cathode spot be always localized on the second zone, named "arc zone" and only on this zone.

The "starting zones" are preferably of small radius of curvature and nearer the one to the other than any other part of the electrodes. Moreover, the surface of these zones must be as even as possible. In this manner, the starting of the discharge takes place between the desired zones.

Each "arc zone" of one of the electrodes must be sufficiently distant from the other electrode as

2

to avoid any discharge starting from this zone, notwithstanding the alterations produced in this zone by the arc discharges. To each "arc zone" may be applied any known means, for instance 5 emissive coating, heterogeneous surface, to facilitate the appearing or the maintaining of a cathode spot on this zone.

Moreover, it is advantageous that the relative positions of the different parts of the electrodes 10 be such that the convection currents, due to the warmth produced by the discharge, or the electro-magnetic forces, or both of them, bring towards the "arc zones" the arc discharge which would, on occasion, have started on another part 15 of the electrode.

As is known, radioactive substances can be placed inside the lightning arrester in order to avoid starting delays.

In the accompanying drawing, given merely by 20 way of example, Figures 1, 2, 3 represent, in axial section, different embodiments of the invention. In these three embodiments, the electrodes are enclosed in a glass enclosure R, filled with gas under low pressure.

25 Referring to Figure 1, which represents a lightning arrester intended to be used when its axis XX is substantially horizontal, in the enclosure R are placed two electrodes, each comprising a lead-in wire D and two cups A, C fixed 30 on this wire. The edge T of each cup A is the part of the corresponding electrode, which is the nearest to the other electrode; this edge T forms the "starting zone" of the electrode and fixes the starting voltage. The edge U of each cup C is 35 provided with a coating of emissive oxides and forms the "arc zone." This lightning arrester comprises behind each electrode, a mica screen B which is intended to prevent the discharge from going around the electrodes and setting on the 40 lead-in wires. The working of this arrester is as follows: when the overvoltage occurs, a glow discharge starts; it begins on a part of edge T, which forms the "starting zone" and spreads by degrees on the surface of the electrode working 45 as a cathode, without deteriorating it if it has been suitably degassed. If the current through the arrester is sufficient, the glow covers the cups A and C and the section Y of lead-in wire which join them. If the current grows further, the 50 discharge turns into an arc discharge; the cathode spot takes place on a point of the edge U of cup C on account of the emissive oxides there located, and which the glow discharge has heated up. The surface alterations, caused by the cathode spot, are confined to the "arc zone" and do not

therefore influence the starting voltage. If, exceptionally, the cathode spot occurs on the cup A, it does not remain there because the convection currents shift upward the discharge.

Referring to Figure 2, which represents a lightning arrester the working of which is the same as above: each electrode comprises a conical part L ending in a round shoulder E of small radius of curvature on which the starting takes place; cone L is joined, by a round shoulder F¹⁰ of small radius of curvature, to a cylindrical part G intended to improve the cooling of cone L; so does the metallic flange H which joins this cone to the lead-in wires J, K. On the surface of round shoulder F, which forms the "arc zone," are imbedded silicon carbide grains, the object of which is to fix the cathode spot from which the arc originates, and to so prevent it from originating on the round shoulder E which forms the "starting zone."

Each electrode is supported by two lead-in wires J, K which are joined together outside the arrester. Mica screens I prevent the arc from going around the electrodes.

Referring to Figure 3, each electrode of the lightning arrester comprises a heavy and polished metal wire N and an helix M, single or double coiled, made of a wire of refractory metal coated with earth-alkaline oxides, the heavy wire and the helix being series connected; the lead-in wire is connected to the end of the helix W not connected to the wire N. Each wire N comprises a section V located at such a distance from the other that the starting of the discharge will occur between these sections under the voltage desired for the starting of the lightning arrester and shall always occur between these sections; the "arc zone" of each electrode is formed by the helices M coated with emissive substance.

The operation of this embodiment is as follows: when the overvoltage occurs, a glow discharge starts between the section V; as the current builds up, the glow spreads and reaches the helix M which it warms up jointly with the Joule effect caused by the flowing of the current which is delivered by the wires N; ultimately the arc strikes, its cathode spot taking place on the helix M. The striking of the arc on the end W of an helix, to which the current is brought, occurs easily, specially since, during the glow discharge, the ohmic voltage drop, due to the resistance of

helix M, causes a potential difference between the end W and the "starting zone" of same electrode.

What I claim is:

- 5 1. A lightning arrester comprising an envelope containing a gaseous atmosphere and two electrodes sealed therein, each electrode comprising a starting zone and an arc zone, the two zones differing in their surface composition, the surface composition of the starting zone being less liable than that of the arc zone to promote the transformation of a glow discharge into an arc discharge, the distance between each electrode and the starting zone of the other electrode being shorter than the distance between said electrode and the arc zone of said other electrode, the discharge starting thus, in any case, on the starting zone and the cathode spot, if the discharge turns into an arc discharge, localizing itself spontaneously on the arc zone and only on this zone.
- 15 2. A lightning arrester according to 1, in which the surface of the arc zone comprises emissive oxides.
- 20 3. A lightning arrester according to 1, in which the "arc zone" surface comprises grains of a semi-conductor.
- 25 4. A lightning arrester according to 1, in which the "arc zone" of each electrode is constituted by a wire of refractory metal helically wound and coated with thermoemissive material, connected in series with a rod which constitutes the "starting zone" of same electrode.
- 30 5. A lightning arrester according to 1, in which the starting zone of each electrode is placed below, at least a part of the arc zone of same electrode.
